SWITCH MOUNTING BRACKET

Rudolf Popp, Valparaiso, Ind., assignor to McGill Manufacturing Company, Valparaiso, Ind., a corporation of Indiana

Application November 2, 1931. Serial No. 572,589

2 Claims. (Cl. 240—85)

My invention relates to switch mounting brackets and has to do more particularly with devices of this character adapted for applying or mounting a switch to a ceiling outlet box and for fastening or securing the usual canopy or panel thereto.

One of the objects of my invention is to provide a support or mounting bracket of the above character, which is simple of construction, cheap to manufacture, and readily applied.

For a better understanding, reference is to be had to the accompanying drawing, in which Fig. 1 is a side elevation, partly in section, showing the device applied to a ceiling outlet box;

Fig. 2 is a top plan view of the bracket removed from the fixture; and

Fig. 3 is a right side elevation of the device.

Referring now more in particular to the preferred form of the device as illustrated, it is shown as applied to a well known form of universal lever switch 1, having universal lever 2 and depending chain 3 for actuating the lever from its normal to its dotted line position as indicated in Fig. 1. The switch is carried by a U-shaped yoke or bracket having an upper leg 4 and lower leg 5 connected by the base portion 6, which is preferably formed at an angle 7 so as to permit the application of canopies with small necks. The yoke or bracket has an upper attaching nipple 8 adapted to thread into a bracket as 9, such as is ordinarily supplied in a wall or ceiling outlet box 10.

A canopy or panel attaching nipple 11 is threaded into the lower leg 5 of the bracket and extends downwardly so as to pass through the panel or canopy 12, which is then fastened in place by a nut 13 which threads onto the nipple 11.

In order to securely fasten the nipples as 8 and 11 to the bracket or yoke member, it has heretofore been the practice to provide a shouldered hub or boss upon the legs of the yoke so that the nipples will thread into the boss and seat upon its shouldered bottom. This has been a comparatively expensive construction and I have simplified and cheapened this by forming a boss 14 upon each of the legs of the yoke, pressing it out of the metal of the leg as indicated in Fig. 3. The inside or last thread is then upset by several small indentations as 15, thus mutilating the innermost thread and forming an effective seat against which the nipple 11 will securely seat.

In order to attach or apply the switch to the yoke I preferably pass the neck of the switch through the base of the yoke and use the ordinary threaded nut 16 to fasten the switch in place. Thus the switch body extends outwardly from the base of the yoke and the operating lever 2 is so positioned that its end is substantially in alignment with the axis of the nipple 11. Thus the depending chain passes freely down

through the nipple 11 and may be readily operated to actuate the lever as indicated by the dotted line position thereof in Fig. 1.

In order to apply canopies or panels of various shapes and designs as are ordinarily employed, the lower nipple 11 is ordinarily made long enough to take any average panel. In shallow panels this nipple 11 will then extend too far outside the face of the panel, so it is cut off by the installer to the proper length so that when the nut 13 is applied to fasten the panel 12 in place, the nipple 11 will be flush with the outer face of the nut 13, thereby presenting a finished appearance.

Although I have shown a particular and well known switch as being used with my improved arrangement, so far as certain features of my invention are concerned other types of switches might be employed. Therefore I do not desire to be limited to the exact structure illustrated and described but aim to cover all that which comes within the spirit and scope of the appended claims.

What I claim as new and desire to protect by Letters Patent of the United States is:—

1. A device for supporting lighting fixtures and the like, including a single-piece U-shaped yoke, means for securing one leg of the yoke to an outlet bracket, a canopy securing nipple extending from the other leg, a universal lever switch, means for securing the switch to the base of the yoke by the neck of the switch with the end of the switch lever substantially opposite the center of the nipple to permit a depending pull chain to extend through the nipple from the end of the lever.

2. A device for supporting lighting fixtures and the like, including a single-piece U-shaped yoke having an upper and a lower leg, an aperture in each of said legs and adjacent the end thereof, an internally threaded boss surrounding said aperture, a plurality of indentations on the inside of said threaded portions, a nipple in each threaded portion seated against said indentations, one of said nipples adapted for securing the yoke to an outlet bracket, and the other said nipple for securing a canopy to the yoke, and a universal lever switch secured to the yoke and positioned to have the end of its lever substantially in alignment with the axis of the last said nipple to permit a pull chain to extend therethrough from the end of the lever.
